HEARING AID APPARATUS

William D. Penn, Dallas, Tex.

Application June 19, 1937, Serial No. 149,271

8 Claims. (CL 179—107)

The invention relates to a method and apparatus for aiding hearing and more particularly to an apparatus and method for selectively accentuating the frequencies to which a particular user is less sensitive than normal.

5 This application is a continuation in part of my application Serial No. 39,073 filed September 3, 1935.

10 The invention is particularly adapted for use in connection with individuals affected with nerve deafness, for in such cases the hearing loss is small at the lower frequencies and much greater at the higher frequencies. Unless the hearing device is designed to amplify selectively, accentuating the higher frequencies to a greater extent than the lower, the lower frequencies to which the individual is nearly as sensitive as a normal individual will be amplified to the threshold of feeling, causing considerable discomfort to the user as well as rendering the sound unintelligible.

15 An object of the invention is, therefore, to provide a device and method of selectively amplifying the frequencies to which a particular person is least sensitive.

20 Another object of the invention is to provide a device, having no more elements than conventional hearing aid devices, which will amplify higher frequencies within the audible range to a greater extent than lower frequencies.

25 Hearing devices employing vacuum tube amplifiers or other types having one or more transformers in circuit can be made to accentuate certain frequencies by providing certain relationships between the transformers and the impedances connected to them. It is therefore a further object of the invention to provide a novel device and method in which a transformer of predetermined characteristics is employed to selectively amplify the frequencies desired.

30 Other objects and advantages of the invention will appear in the following detailed description of the preferred embodiments of the invention shown in the attached drawings of which

35 Fig. 1 is a schematic diagram of one embodiment of the invention using a single transformer; and

40 Fig. 2 is a schematic diagram of a modification thereof in which two transformers are employed.

45 Fig. 3 is a schematic diagram of a further modification of this invention, showing an adjustable type transformer.

50 Figs. 4, 5 and 6 are schematic diagrams employed for the purpose of illustrating and facilitating the explanation of features of this invention.

55 Referring more particularly to the drawings, 10 indicates a microphone, 11 indicates a coupling transformer between the microphone and amplifier tube 12 and 13 indicates a telephone receiver unit or bone conduction unit. The mi-

crophone 10 is connected to the primary 14 of the transformer 11, in series with a suitable source of voltage shown as a microphone battery 15. The secondary 16 of the transformer 11 has a suitable high resistance 17 connected thereacross with a variable contact 18 to provide a volume control. Suitable sources of potential, shown as batteries 19 and 20, are provided for the filament, grid and plate circuits respectively of the tube 12.

60 As has been hereinbefore indicated, the circuit shown in the drawings can be made to selectively amplify certain frequencies by a proper relation between transformer and terminating impedances. The transformer I prefer to employ is provided with windings of very low distributed capacity and the leakage inductance referred to the primary winding is preferably less than one millihenry. These conditions may be obtained by making the physical dimensions of the transformer extremely small. For example, the transformer may be made approximately 1.2 inches wide, 1.1 inches high and 1.0 inch overall thickness. In any event, the only necessary restriction is that the leakage inductance referred to the primary winding and the distributed capacity (including the capacity of the associated circuits connected to the transformer) referred to the primary, be of such a magnitude compared to the impedance connected to the primary winding such that they do not appreciably affect the circuit at the lower audio frequencies below the first resonant frequency of the transformer. The first resonant frequency is that due to resonance between the primary inductance and the effective capacity referred to the primary.

65 Insofar as the action of the transformer itself is concerned it may be shown that in the range below the first resonant frequency the voltage step-up is given by the following equation:

$$\frac{e_b}{e_o} = \frac{(n_2/n_1)k}{\sqrt{(1+R_o/R^1)^2 + (R_o/L_1 w k^2)^2}} \quad (1)$$

70 and the decibel loss due to the shunting effect of the primary is

$$N = 20 \log_{10} \left| \frac{\sqrt{(1+R_o/R^1)^2 + (R_o/L_1 w k^2)^2}}{\sqrt{(1+R_o/R^1)^2}} \right| \quad (2)$$

75 In these equations:

80 e_b = the voltage across the load circuit at a given frequency.

85 e_o = the open circuit output voltage of the microphone 10 at the same frequency.

90 R_o = the internal impedance of the microphone.

95 wL_1 = the open circuit reactance of the primary 14 of the transformer 11. $w = 2\pi f$.

100 R^1 = the impedance of the control 17 referred to the primary $= (n_1/n_2)^2$ times resistance of 17.

105 k = the co-efficient of coupling of the transformer.

The vacuum tube and its load may easily be adjusted to give a substantially constant amplification over the entire audio frequency range under consideration and hence the voltage ratio given by the above equation is in effect merely multiplied by a constant factor due to the vacuum tube.

From Equation 1 it is seen that in the range for which the equation applies the voltage ratio depends, for any given value of R_0 and n_2/n_1 upon the ratio $R_0/L_1 w k^2$. For a closely coupled transformer k^2 is approximately equal to unity.

By choosing the proper value of $R_0/L_1 w k^2$ the voltage amplification can be caused to fall off as the frequency decreases.

Equation (2) gives the decibel loss due to the shunting effect of the primary. If the ratio $R_0/L_1 w k^2$ is sufficiently small Equation (2) would become

$$20 \log_{10} \left| \frac{\sqrt{(1+R_0/R^1)^2}}{\sqrt{(1+R_0/R^1)^2}} \right| = 0$$

and there would be no loss due to the shunting effect.

If the secondary of the transformer 11 is assumed to work open circuited then $R^1 = \infty$ and

$$\frac{e_2}{e_0} = \frac{(n_2/n_1)k}{\sqrt{1+(R_0/L_1 w k^2)^2}}$$

and

$$N = 20 \log_{10} \sqrt{1+(R_0/L_1 w k^2)^2}$$

From the above analysis it is seen by using Equations 1 and 2 the transformer and its associated impedance can be related as to attenuate the low audio frequencies with respect to the higher audio frequencies.

As a specific example of the application of the present invention, assume that audiometric measurements of the deafness of a particular deaf person show that the amplification must be attenuated approximately 20 decibels at 60 c. p. s. If the volume control 17 and the turn ratio n_2/n_1 is such that $R_0/R^1 = 1$ and $R_0 = 200$ ohms and $k = 1$, Equation 2 becomes

$$45 \quad 20 = 20 \log_{10} \left| \frac{\sqrt{(1+1)^2 + (R_0/L_1 w)^2}}{\sqrt{(1+1)^2}} \right|$$

or

$$50 \quad \log_{10} \left| \frac{\sqrt{4 + (R_0/L_1 w)^2}}{2} \right| = 1$$

hence

$$(R_0/L_1 w)^2 = 396, w = 2\pi/ = 377$$

so

$$55 \quad L_1 = \frac{200}{377 \times 19.9} = 0.0266 = 26.6 \text{ m. h.}$$

Thus for the assumed conditions we have obtained from Equation 2 the value of L_1 necessary to attenuate the 60 c. p. s. frequency 20 decibels below the normal gain of the device.

60 It is understood, of course, that the transformer may be placed in other positions than that shown in Fig. 1, without departing from the spirit of my invention. For example, as shown in Fig. 2, the receiving unit 13 is coupled to the output of the tube 12 by a transformer 22 having a primary 23 in the plate circuit of the tube 12, and a secondary 24 connected to the tube 12a the output of which is connected to the receiving unit 13. This second transformer may be employed 65 to selectively amplify the desired frequencies. In this case, the ratio determining the frequency response characteristic of the transformer 22 is $r_p/L_1 w$ instead of $R_0/L_1 w$ as in Equations 1 and 2, where r_p is the variational plate resistance 70 of the tube 12 and wL_1 is the open circuit react-

ance of the primary 23. Also by utilizing both transformers of Fig. 2, the range of control may be advantageously extended.

In the case of the transformer 22, in the plate circuit of the vacuum tube, the equivalent a. c. voltage effective in the plate circuit acts in series through the variational or dynamic plate resistance, r_p of the tube.

The voltage acting in the plate circuit is ue_t where u is the amplification factor of the tube 12 and e_t the voltage at the grid of the tube. In other words, the vacuum tube can be replaced by a voltage ue_t acting in series with the plate resistance r_p of the tube, as far as external performance is concerned. This is represented 15 schematically in Fig. 4.

Equation (1) then becomes:

$$\frac{e_2}{e_0} = \frac{u(n_2/n_1)k}{\sqrt{(1+r_p/R^1)^2 + (r_p/L_1 w k^2)^2}}$$

20

For any particular stage then of the amplifier, e_2 = voltage across the load circuit, e_0 = the voltage applied to the grid of the tube. This equation applied to the transformer coupled stage of the amplifier indicated between the broken lines 25 A-A and B-B of Fig. 5. This portion of the circuit of Fig. 5 is equivalent to the circuit shown in Fig. 6. This equation is the same as Equation (1) except that the dynamic plate resistance of the vacuum tube has been substituted for the 30 microphone resistance, e_t has been substituted for e_0 and the right hand member of the equation has been multiplied by the factor u to take account of the gain of the vacuum tube.

Where the ratio of the turns of the transformer 35 secondary 16 to the turns of the primary 14 is such that the equivalent load resistance referred to the primary is large in comparison to the impedance of the microphone 10 so as to make the ratio of the impedance of said microphone to the 40 equivalent load resistance referred to the primary negligible in comparison to unity, Equation 1 resolves itself into the following equation:

$$45 \quad \frac{e_2}{e_0} = \frac{A}{\sqrt{1 + \left(\frac{R_0}{wL_1} \right)^2}}$$

The above relation shows that the amplification

$$\frac{e_2}{e_0}$$

50

depends upon the ratio

$$\frac{R_0}{wL_1}$$

which is the ratio of the microphone impedance 55 to the reactance of the transformer primary. Since the smallest value which the expression under the radical can have in the above equation is unity, the factor A also represents the maximum value of amplification possible. The value of the expression wL_1 increases with frequency which indicates that the amplification increases with frequency. For example, at the frequency which makes $R_0 = wL_1$, the amplification will be 70.7% of the maximum value and at three times this 60 frequency the amplification will be 95% of this maximum. Thus, by selecting a proper ratio of 65

$$\frac{R_0}{wL_1}$$

70

the amplification at the low frequencies can be made a small fraction of the maximum available amplification and as the frequency increases the amplification will also increase until the maximum value is reached.

75

As a specific example of the application of the present invention, it is assumed that audiometric measurements of the deafness of a particular deaf person shows that the amplification at 4000 c. p. s. must be approximately ten times that at 60 c. p. s. As a first approximation the expression

$$\frac{1}{\sqrt{1 + \left(\frac{R_0}{wL_1}\right)^2}}$$

when the frequency is 60 c. p. s. is made equal to $\frac{1}{10}$. This requires that the ratio

$$\left(\frac{R_0}{wL_1}\right)^2 = 99$$

or

$$L_1 = \frac{R_0}{w\sqrt{99}}$$

If the microphone impedance in the particular circuit is, for example, 200 ohms, then

$$L_1 = \frac{200}{2\pi \times 60\sqrt{99}} = 0.0534 \text{ henry}$$

Using this value for the primary inductance in the equation first given the amplification is:

- 0.1 of the maximum at 60 c. p. s.
- 0.64 of the maximum at 500 c. p. s.
- 0.81 of the maximum at 1000 c. p. s.
- 0.95 of the maximum at 4000 c. p. s.

This is a very close approach to the ideal characteristic desired and no further calculations are necessary.

In Fig. 3 I have shown another modification of a device having a transformer 11 with an adjustable frequency response characteristic. In this modification the microphone 10 connected in series with a battery 15 is connected to an alterable tap primary 14 of the transformer 11. By means of the taps 30 the effective inductance of the primary may be altered and hence the frequency response characteristic changed. As has been shown elsewhere in the specification, with the other elements fixed in the systems disclosed in Fig. 3, the amplification obtainable depends primarily upon the ratio of the impedance of the microphone 10 to the reactance of the primary 14 of the transformer. This ratio will vary with different frequencies and by changing the connection of the microphone 10 with the taps 30, the variation of this ratio can be changed to cause the system to amplify selectively the frequencies to which the particular deaf person being aided is least sensitive. Also the various taps 30 of the primary 14 may be interconnected in various ways to change the frequency response characteristic of the transformer, for various impedances may be connected across the taps either singly or in combination to vary the selective amplification of the system. It is pointed out that if the deafness is slight, the amplifying tubes may be omitted and the adjustable frequency responsive transformer used to couple the microphone 10 to the receiving device 18.

While I have disclosed the preferred embodiments of my invention and have given specific examples thereof, it is understood that I am not to be limited thereto, but that the invention may be varied within the scope of the following claims:

70 I claim:

1. Hearing aid apparatus adapted selectively to attenuate the low audible frequencies and amplify the high audible frequencies comprising: a microphone pick-up adapted to translate mechanical vibrations into corresponding variable

electrical currents, said microphone pick-up having a predetermined impedance characteristic, a transformer having primary and secondary windings, connections between said microphone pick-up and said primary, and a load circuit including a reproducing device connected to said secondary, the open circuit impedance of the primary and the impedance of said microphone being such that the voltage ratio e_b/e_0 of the said apparatus is equal to

$$\frac{(n_2/n_1)k}{\sqrt{(1 + R_0/R^1)^2 + (R_0/L_1 w k^2)^2}}$$

wherein e_b is the voltage across the load circuit, e_0 is the open circuit voltage of the microphone, n_2/n_1 is the turn ratio of the transformer, R_0 is the microphone impedance, R^1 is the effective load impedance referred to the primary, k is the coefficient of coupling of the transformer, and wL_1 is the open circuit reactance of the primary, whereby the low audible frequencies are attenuated selectively to the high audible frequencies.

2. Hearing aid apparatus adapted selectively to attenuate the low audible frequencies and amplify the high audible frequencies comprising: a microphone pick-up adapted to translate mechanical vibrations into corresponding variable electrical currents, said microphone pick-up having a predetermined impedance characteristic, a transformer having primary and secondary windings, connections between said microphone pick-up and said primary, and a load circuit including a reproducing device connected to said secondary, the ratio of the turns of said secondary to the turns of said primary being such that the equivalent load resistance referred to the primary is large in comparison to the impedance of said microphone so as to make the ratio of the impedance of said microphone to the equivalent load resistance referred to the primary negligible in comparison with unity, the open circuit impedance of the primary and the impedance of said microphone being such that the voltage ratio e_b/e_0 of the said apparatus is equal to

$$\frac{A}{\sqrt{1 + \left(\frac{R_0}{wL_1}\right)^2}}$$

wherein e_b is the voltage across the load circuit, e_0 is the open circuit voltage of the microphone, A is a circuit constant, R_0 is the mean microphone impedance and wL_1 is the effective reactance of the primary, whereby the low audible frequencies are attenuated selectively to the high audible frequencies.

3. Hearing aid apparatus adapted selectively to attenuate the low audible frequencies and amplify the high audible frequencies comprising: a microphone pick-up adapted to translate mechanical vibrations into corresponding variable electrical currents, said microphone pick-up having a predetermined impedance characteristic, a transformer having primary and secondary windings, connections between said microphone pick-up and said primary, and a load circuit including a reproducing device connected to said secondary, the open circuit impedance of the primary and the impedance of said microphone being such that the voltage ratio e_b/e_0 of the said apparatus is equal to

$$\frac{(n_2/n_1)k}{\sqrt{(1 + R_0/R^1)^2 + (R_0/L_1 w k^2)^2}}$$

wherein e_b is the voltage across the load circuit, e_0 is the open circuit voltage of the microphone, n_2/n_1 is the turn ratio of the transformer, R_0 is

the microphone impedance, R^1 is the effective load impedance referred to the primary, k is the co-efficient of coupling of the transformer, and wL_1 is the open circuit reactance of the primary, 5 the ratio $R_0/L_1 w k^2$ in the aforesaid equation being of such a value that the voltage amplification e_b/e_0 is caused to fall off as the frequency decreases, whereby the low audible frequencies are attenuated selectively to the high audible 10 frequencies.

4. Hearing aid apparatus adapted selectively to attenuate the low audible frequencies and amplify the high audible frequencies comprising: a microphone pick-up adapted to translate mechanical 15 vibrations into corresponding variable electrical currents, said microphone pick-up having a pre-determined impedance characteristic, a transformer having primary and secondary windings, connections between said microphone pick-up and 20 said primary, a vacuum tube amplifier connected to said secondary winding, and a load circuit including a reproducing device connected to said vacuum tube amplifier, the open circuit impedance of the primary and the impedance of said 25 microphone being such that the voltage ratio e_b/e_0 of the said apparatus is equal to

$$\frac{(n_2/n_1)A}{\sqrt{(1+R_0/R^1)^2+(R_0/L_1 w k^2)^2}}$$

30 wherein e_b is the voltage across the load circuit, e_0 is the open circuit voltage of the microphone, n_2/n_1 is the turn ratio of the transformer, R_0 is the microphone impedance, R^1 is the effective load impedance referred to the primary, A is a 35 circuit constant including the amplification of the vacuum tube amplifier, k is the coefficient of coupling of the transformer, and wL_1 is the open circuit reactance of the primary, whereby the low audible frequencies are attenuated selectively to 40 the high audible frequencies.

5. Hearing aid apparatus adapted selectively to attenuate the low audible frequencies and amplify the high audible frequencies comprising: a microphone pick-up adapted to translate mechanical 45 vibrations into corresponding variable electrical currents, said microphone pick-up having a pre-determined impedance characteristic, a transformer having primary and secondary windings, connections between said microphone pick-up and 50 said primary, a vacuum tube amplifier connected to said secondary, and a load circuit including a reproducing device connected to said vacuum tube amplifier, the open circuit impedance of the primary and the impedance of said 55 microphone being such that the voltage ratio e_b/e_0 of the said apparatus is equal to

$$\frac{(n_2/n_1)A}{\sqrt{(1+R_0/R^1)^2+(R_0/L_1 w k^2)^2}}$$

60 wherein e_b is the voltage across the load circuit, e_0 is the open circuit voltage of the microphone, n_2/n_1 is the turn ratio of the transformer, R_0 is the microphone impedance, R^1 is the effective load impedance referred to the primary, A is a 65 circuit constant including the amplification of the vacuum tube amplifier, k is the coefficient of coupling of the transformer, and wL_1 is the open circuit reactance of the primary, the ratio $R_0/L_1 w k^2$ in the aforesaid equation being of such a value 70 that the voltage amplification e_b/e_0 is caused to fall off as the frequency decreases, whereby the low audible frequencies are attenuated selectively to the high audible frequencies.

6. Hearing aid apparatus adapted selectively 75 to attenuate the low audible frequencies and am-

plify the high audible frequencies, comprising: a device adapted to translate mechanical vibrations into corresponding variable electrical currents, an amplifier therefor having at least one transformer coupled stage of amplification, a 5 transformer for said amplifier, a vacuum tube for said amplifier, an output circuit including a reproducing device connected to said amplifier, the open circuit reactance of the primary of said transformer and the dynamic plate resistance of the vacuum tube connected to said primary being such that the voltage ratio e_b/e_0 of said transformer coupled stage is equal to 10

$$\frac{u(n_2/n_1)k}{\sqrt{(1+r_p/R^1)^2+(r_p/L_1 w k^2)^2}} \quad 15$$

wherein e_b is the voltage across the load circuit connected to the secondary of said transformer, e_0 is the voltage applied to the grid of said vacuum tube, u is the amplification factor or variational plate voltage ratio, n_2/n_1 is the turn ratio of the transformer, r_p is the dynamic plate resistance, R^1 is the effective load impedance referred to the primary, k is the co-efficient of coupling of the transformer, and wL_1 is the open circuit reactance of the primary, whereby the low audible frequencies are attenuated selectively to the high audible frequencies. 20 25

7. Hearing aid apparatus adapted selectively to attenuate the low audible frequencies and amplify the high audible frequencies comprising: a pick-up device adapted to translate mechanical vibrations into corresponding variable electrical currents, an amplifier therefor including at least one vacuum tube and transformer coupled stage of amplification, a transformer and a vacuum tube for said amplifier, an output circuit including a reproducing device connected to said amplifier, the open circuit resistance of the primary of said transformer and the dynamic plate resistance of the vacuum tube connected to the primary of said transformer being such that the voltage ratio e_b/e_0 of said transformer coupled stage is equal to 30 35 40

$$\frac{u(n_2/n_1)k}{\sqrt{(1+r_p/R^1)^2+(r_p/L_1 w k^2)^2}} \quad 45$$

wherein e_b is the voltage across the load circuit connected to the secondary of said transformer, e_0 is the voltage applied to the grid of said vacuum tube, u is the amplification factor or variational plate voltage ratio of said vacuum tube, n_2/n_1 is the turn ratio of the transformer, r_p is the dynamic plate resistance R^1 is the effective load impedance referred to the primary, k is the co-efficient of coupling of the transformer, and wL_1 is the open circuit reactance of the primary, the ratio $r_p/L_1 w k^2$ in the aforesaid equation being of such a value that the voltage amplification e_b/e_0 is caused to fall off as the frequency decreases, whereby the low audible frequencies are attenuated selectively to the high audible frequencies. 50 55 60

8. Hearing aid apparatus adapted selectively to attenuate the low audible frequencies and amplify the high audible frequencies comprising: a pick-up adapted to translate mechanical vibrations into corresponding variable electrical currents, said pick-up having a predetermined impedance characteristic, a transformer having primary and secondary windings, connections between said microphone pick-up and said primary, a vacuum tube having an input circuit connected to said secondary winding, a second transformer having a primary connected to the plate circuit 70 75 75

of said vacuum tube, and a load circuit including a reproducing device connected to the secondary of said second transformer, the open circuit reactance of the primary of said second transformer and the dynamic plate resistance of said vacuum tube connected to the primary of said second transformer being such that the voltage ratio e_b/e_g of the stage including said vacuum tube and said second transformer is equal to

$$\frac{u(n_2/n_1)k}{\sqrt{(1+r_p/R^1)^2 + (r_p/L_1w^2k^2)^2}}$$

wherein e_b is the voltage across the load circuit

connected to the secondary of said second transformer, e_g is the voltage applied to the grid of said vacuum tube, u is the amplification factor or variational plate voltage ratio of said vacuum tube, n_2/n_1 is the turn ratio of the transformer, r_p is the dynamic plate resistance, R^1 is the effective load impedance referred to the primary of said second transformer, k is the co-efficient of coupling of said second transformer, and wL_1 is the open circuit reactance of the primary of said second transformer, whereby the low audible frequencies are attenuated selectively to the high audible frequencies.
